UNITED STATES PATENT OFFICE.

FREDERICK W. LINAKER, OF DUBOIS, PENNSYLVANIA, ASSIGNOR TO THE VULCAN SOOT CLEANER CO., OF PITTSBURG, PA., OF DUBOIS, PENNSYLVANIA, A CORPORATION OF NEW JERSEY.

FUEL-ECONOMIZER SOOT-CLEANER.

1,160,730.

Specification of Letters Patent. Patented Nov. 16, 1915.

Application filed November 3, 1914. Serial No. 370,126.

To all whom it may concern:

Be it known that I, FREDERICK W. LINAKER, subject of the King of England, residing at Dubois, in the county of Clearfield and State of Pennsylvania, have invented certain new and useful Improvements in Fuel-Economizer Soot-Cleaners, of which the following is a specification.

This invention relates to improvements in fuel economizer soot cleaners and has for its primary object to provide in an economizer, a cleaning fluid distributing pipe or pipes for directing a cleaning fluid, preferably steam, upon the exterior surfaces of the tubes of the economizer whereby to effectually free the latter of soot.

A further object of the invention is to provide in an economizer, a fluid distributing pipe or pipes so constructed and arranged as to discharge the cleaning fluid between the rows of tubes of the economizer in streams along lines or paths radial to the axis or axes of the distributing pipe or pipes.

A still further object is to provide in an economizer, a soot cleaning means in the form of a fluid-distributing pipe or pipes adapted to discharge cleaning fluid in jets or streams among and between the economizer tubes, and capable of oscillatory movement whereby to cause said distributing pipe or pipes to vary the angularity or obliquity of the streams of cleaning fluid, thereby adapting the latter to cover a wide radial area and to thus effect the removal of accumulated soot from all of the rows of the economizer tubes.

Fuel economizers, as is well known, are utilized for the purpose of heating water preliminary to its introduction into the boiler, and for this purpose use is made of the waste gases and other products of combustion, the economizer being generally located in the path of travel of such production, leading from the boiler or boilers to the chimney or stack, the economizers comprising a plurality of spaced vertically-extending tubes, the upper and lower ends of which are connected by headers to provide a circulation of water therethrough. As the tubes are located in the path of travel of the products of combustion, the outer surfaces of the tubes quickly collect soot particles carried by such products, destroying the

maximum application of heat to the tubes. 55 Tube cleaners which travel vertically over the outer surfaces of the tubes have heretofore generally been employed for removing such soot particles and scale as may collect on the tubes, these cleaners acting in a manner similar to a scraper. Difficulty has been encountered in the use of cleaners of this type for economizers, in that the scraping cleaners oftentimes may not be operated to effectually clean the tube throughout its 60 length, and also that they drive or force the soot ahead of them, causing it to collect in masses which are not easily carried off by the natural draft.

To overcome the above and other objections 70 to the cleaning of economizer tubes by a scraping action, I arrange among the tubes as heretofore stated, a distributing pipe or pipes for a cleaning fluid, capable of being operated at any time without closing down 75 the operation of the furnace or the economizer, and which in operation in addition to effectually cleaning the economizer tubes of soot, aid the natural draft in carrying off the removed particles, and enabling me at all 80 times to procure a maximum amount of service from the economizer.

The nature of the invention will be readily understood as the same is hereinafter disclosed, and the said invention consists in the 85 improved construction, combination and arrangement of parts, hereinafter fully described, illustrated in the accompanying drawings, and particularly pointed out in the appended claim.

In the drawings, in which similar reference characters indicate similar parts in each of the views: Figure 1 is a plan view partly broken away of an economizer of the well known Green type, with a soot cleaner in 95 accordance with my invention applied thereto. Fig. 2 is a side elevation of the same partly broken away, and Fig. 3 is a detail side elevation of a modified means for operating the distributing pipe.

A fuel economizer of the Green type comprises a casing or setting 1 which incloses the vertically-disposed economizer tubes 2 connected in the usual manner at the upper and lower ends by headers 3. The tubes 2 in this type of an economizer are in parallel rows, and in order to effectually remove the accumulated soot from the tubes, it is desir-

able to project the cleaning agent in jets or streams along paths or lines between the rows of tubes 2 at substantially right angles to the axis or axes of the distributing pipe 4 or pipes that is arranged among the tubes for cleaning purposes.

In the here chosen illustration of my invention, I have shown a plurality of distributing pipes 4, these pipes being journaled in 10 the opposite side walls of the setting or casing 1. Obviously, but a single pipe, or as many of the pipes as desired may be arranged, according to the size of the economizer, in which the cleaner is arranged. 15 Whether there be one or more pipes, each pipe is closed at its inner end, its outer end being in communication with a branch pipe 6 connected with a supply pipe 7, which latter is provided with the usual shut-off, drain 20 valve, etc. Each branch pipe 6 is also provided with a shut-off valve 6'. Each pipe 4 is provided with spaced nozzles 8 so disposed with relation to the axis of the pipe, that the cleaning agent is directed in jets or streams 25 along paths or lines between the rows of tubes 2 at substantially right angles to the pipe or pipes to remove accumulations of soot from the outer surfaces of the tubes, these paths or lines upon which the jets or 30 streams of the cleaning agent are projected, being clearly illustrated in Fig. 1 of the drawings. In order that the pipe or pipes 4 may be oscillated or partially rotated, the outer ends of these pipes connect by means 35 of a swivel joint 9 with the branch pipe 6, suitable means being provided for operating the pipe or pipes 4. This means may be a hand wheel or handle 9^a as in Fig. 3 on each pipe 4, or it may be a sprocket wheel 10 upon each pipe 4, over which passes a 40 sprocket chain 11.

The operation of the means above described will be readily understood. A cleaning fluid, preferably steam, being introduced 45 into the distributing pipe through the connection shown, or other suitable supply and feed connections, will be discharged through the nozzles 8 and projected in jets or streams along parallel lines or paths between the 50 several circulating tubes of the economizer. The oscillating movement of the pipe or pipes varies the radial paths of the streams

of fluid issuing from the discharge nozzles, insuring a thorough cleaning of the water circulating tubes of the economizer throughout their length, such wide diffusion of the cleaning fluid permitting it to permeate all of the spaces between the water tubes and any surface within the economizer casing or setting where soot may find lodgment. 55

While other means for oscillating the distributing pipe may be employed, I have found the simple hand-operated means herein shown and described admirably adapted for effecting the movement of the pipe or 60 pipes, and as this mechanism is located entirely outside the casing or setting, it may be operated conveniently and easily, and applied to, repaired, or removed from the pipe 65 with little effort and expense. 70

It will be understood that the invention is susceptible to modifications in its structural details, such as in the manner of operating the distributing pipes, and in the number or distribution of these pipes among the tubes 75 so as to effectually clean the latter, and like modifications as may fall within the terms and scope of the invention as claimed.

What I claim as new is:—

The combination with a fuel-economizer 80 system having parallel rows of vertical water-circulating tubes and located in the path of travel of the products of combustion, and a setting inclosing said tubes, of a fluid distributing pipe journaled in opposite walls 85 of the setting and disposed between two adjacent rows of the tubes of the economizer and provided with discharge nozzles so disposed with relation to the pipe as to discharge a cleaning agent between the rows of 90 tubes in jets or streams on parallel lines or paths at right angles to the axis of the pipe, the pipe being rotatively mounted whereby to vary the obliquity of said jets or streams with respect to the horizontal axes of the 95 water-circulating tubes, and means exteriorly of the economizer setting for rotating said fluid distributing pipe.

In testimony whereof I affix my signature in presence of two witnesses.

FREDERICK W. LINAKER.
